EDGAR N. GOODLETT, OF LOS ANGELES, AND JOHN B. GOODWIN, OF LONG BEACH, CALIFORNIA.

SEPARABLE CORE FOR CONCRETE WORK.

1,290,972.

Specification of Letters Patent.

Patented Jan. 14, 1919.

Application filed July 25, 1916. Serial No. 111,242.

To all whom it may concern:

Be it known that we, EDGAR N. GOODLETT, a citizen of the United States, and a resident of the city of Los Angeles, county of Los Angeles, State of California, and JOHN B. GOODWIN, a citizen of the United States, residing in the city of Long Beach, county of Los Angeles, State of California, have jointly invented a new and useful invention—to wit, Separable Cores for Concrete Work, of which the following is a specification.

The invention relates in its present embodiment particularly to cores for forming recesses in concrete railway ties, among the objects of the invention are to form a core that may readily be removed from the concrete mass when the latter has set avoiding the danger of the core becoming permanently embedded in the concrete. Also permitting the removal of the core with the minimum amount of disturbance endangering the integrity of the concrete mass before crystallization is complete.

In the specification and the annexed drawings we illustrate the invention in the form that we consider the best, but it is to be understood that we do not limit ourselves to such form because the said invention may be embodied in other forms, it is also to be understood that in and by the claims following the description we desire to cover the invention in whatever form it may be embodied.

In the accompanying one sheet of drawings:

Figure 1 is a perspective view from beneath of a separable core constructed and assembled in accordance with this invention.

Fig. 2 is a similar view from above of the same.

Fig. 3 is a fragmentary enlarged detail illustrating the manner of joining the various parts of the core.

Fig. 4 is a further enlarged fragmentary detail of the same.

It is common practice in forming recesses in concrete masses to construct a core of the desired contour, of wood, metal or any other suitable material, hollow or solid according to conditions. This form of core is subject to the disadvantage that the shrinkage of the concrete mass in crystallizing is apt to bind the core in the mass, in such a

manner that it must be forcibly driven out, endangering the integrity of the concrete in the act of dislodging the core by this method.

The present invention contemplates forming the core of a number of interlocking parts so constructed and combined that they present the maximum resistance against pressure or distortion when assembled, yet may be easily disassembled inwardly, for the purpose of removing the core in parts from the recess formed thereby in the concrete mass.

In detail the structure illustrated in the drawings includes: the end sections alike in construction and comprising the plane 1 tapering from the base 2 to the shoulder line 3. The shoulder 4 is offset at an angle to the plane 1 and joins the uprising plane 5 tapering away from the shoulder 4. The lateral edges of the plane 1 are bent at an angle to the plane at the point 6 and terminate in a loop 7 (see Fig. 4). The lateral edges of the plane 5 are bent at an angle thereto terminating in the flanges 8 (see Fig. 3). The lower edges of the base 1 of the plane 2 are bent inwardly as at 9 to add rigidity to the plane and to form a smooth edge at this point.

The side sections are alike in construction and comprise the main plane 10 tapering from the base line 11 to the shoulder line 12 and terminating in the flange 13 forming a continuation of the shoulder 4 which they overlie at the ends. The lateral edges of the main plane 10 are turned inwardly parallel with the plane and terminate in the flanges 14 (see Fig. 4). These flanges 14 lie within the loop 7 formed on the lateral edges of the end sections 1, with which they form a lock joint at the four corners of the core to maintain the end and side sections in rectangular assemblage.

From the shoulder flange 13 the plane 15 rises to the top of line 16, forming the edge of the plane 15. The lateral edges of the plane 16 are turned at right angles to form the flange 17, overlying the flanged corners of the plane 5 of the end section. The base line 11 of the side sections is flanged inwardly at 17, as at 9 on the end sections, and for the same purpose. To give stability to the top of the core and prevent its collapsing inwardly, the top 18 is provided, the corners of the top are cut away as at 19 to clear the overlapping flanges of the end and side sections. The 110

plane of the top 18 is depressed below the edges to form the loops or grooves 20 and 21, respectively engaging the upper edges of the planes 5 and 15, holding the end and side sections in rigid assembly and preventing distortion of the core at the top.

To prevent the collapsing inwardly of the end sections and the side sections at the bottom, the insert 22 is provided, the edges 10 23 of which are flanged downwardly to bear against the end sections and the side sections respectively, when the insert is in position in the core. The angle of the flanges 23 and 24 conform to the angle of the end planes 15 1 and 10 and exert a wedging action when the insert is forced into position holding the lower portion of the core in rigid assembly. For convenience in handling the insert, the opening 25, is cut out of the center thereof. 20 For convenience in assembling the core, it is desirable to make up a form following the contour of the interior of the core between the planes 1—1 of the end sections and the planes 10—10 of the side sections, this form 25 having the outwardly curled edges 27 and 28. The sequence in assembling the core, is to place the end sections in position on the form within the curled edges 27, then insert the lower edges of the flanges 14 on the side 30 sections, within the loops 7 on the end sections and slide the side section down until the flange 13 rests upon the shoulders 4 of the end sections; then place the cover 18 in position and force it downward so that its 35 edges 20 and 21 engage the upper edges of the end and side sections; then remove the core from the form 26 and insert the retainer 22. The core is then in complete and self 40 contained assembly, ready for placing in the mold to have the concrete mass flowed around it.

When this concrete mass has set sufficiently to permit the removal of the mold therefrom the cores embedded in the concrete mass can be removed by pressure on the top 18 forcing the whole assembly of the core out of the mass of the concrete, or should the concrete mass have set so as to bind the core it can be disassembled for 45 removal.

This disassembling of the core is accomplished by removing the retainer 22, which permits the end sections to collapse inwardly disengaging from the flanged edges 55 14 of the side sections, which permits the end sections to be lifted out of the concrete

mass disengaging from the edges 20 of the cover 18; with the end sections removed from the recess, the side sections can be similarly moved inward and removed from the recess, disengaging from the edges 21 of the cover. It is obvious that no violent action is necessary in disassembling and removing the core from the concrete mass, thus saving the concrete from vibration and jar likely to interfere with its proper setting and form. The cores are so proportioned that the cover 18 projects into or through the mold so as to project above the surface of the concrete mass to prevent it becoming embedded therein for obvious reasons. To prevent lodgment of grout or flowing concrete into the top of the cover 18 while pouring into the mold, the top may be covered by a suitable cap as indicated in dotted lines in Fig. 1. This, however, is not necessary to the proper functioning of the core.

We do not wish to be understood as confining this invention to the particular form and method of interlocking the several parts 80 of the assembly as they must vary with the modifications in the contour and general application of the core to meet particular conditions, many variations being possible within the spirit of this invention.

Having thus described this invention, what we claim and desire to cover by Letters Patent is:

1. A core including interlocking side and end walls, said walls being offset to form a continuous horizontal shoulder around the core, a removable top having grooves to receive the upper edges of the walls and a removable retaining member within said core engaging the walls.

2. A collapsible core having side and end walls, interlocking means connecting the meeting edges of said walls, the core being of a reduced size adjacent its upper end, a top fitting within the core and having grooves to receive the upper edges of the walls and removable means within the core to prevent collapsing thereof.

In testimony whereof, we have hereunto set our hands at Los Angeles, California, 105 this 5th day of July, 1916.

EDGAR N. GOODLETT.
JOHN B. GOODWIN.
